UNITED STATES PATENT OFFICE.

WILLIAM WHITE, OF PASSAIC, NEW JERSEY, ASSIGNOR TO CLARENCE WHITMAN & CO., OF NEW YORK, N. Y.

DESIGN FOR A BED-SPREAD.

SPECIFICATION forming part of Design No. 24,126, dated March 19, 1895.

Application filed January 30, 1895. Serial No. 536,720. Term of patent 3½ years.

To all whom it may concern:

Be it known that I, WILLIAM WHITE, a subject of the Queen of Great Britain, residing in Passaic, Passaic county, and State of New Jersey, have invented and produced a new and original Design for Bed-Spreads, of which the following is a specification.

The leading feature of my design consists of a bed-spread of essentially the configuration 10 and representation shown in the accompanying drawing which exhibits a quarter section of a bed-spread partly in full detail and partly in outline.

In the drawing, *a a a* are parallelograms 15 presenting plaid effects which are flanked by parallelograms *b* presenting bird's eye effects. Adjacent to some of these parallelograms presenting bird's eye effects are placed parallelograms *c c c c c* presenting checker-board ef-

fects and *d* presenting lattice-work effects. 20 These various parallelograms are alternated and located, as shown in the drawing, and constitute the field of the spread. This field is bordered upon one side by a band *e* and upon the other side by a band *f*, the entire 25 spread being bordered by a band *A* which consists of juxtaposed parallelograms *g* presenting lattice-work effects, triangles and squares *h i* presenting checker-board effects, and parallelograms *k* presenting a banded 30 effect.

What I claim is—

The design for a bed-spread, substantially as herein shown and described.

WILLIAM WHITE.
